ATTORNEY

UNITED STATES PATENT OFFICE.

THOMAS H. THOMAS, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA.

VARIABLE-LOAD BRAKE.

Application filed July 7, 1926. Serial No. 120,939.

This invention relates to variable load brake devices and is more particularly in the nature of an improvement on the variable load brake device described in my pending application, Serial No. 79,549, filed January 6, 1926.

With the construction shown in the above application, graduated release is effected by the use of a timing reservoir while according to the present application, means are provided, whereby the release is graduated in proportion to the load on the car.

In the accompanying drawing; Fig. 1 is a diagrammatic sectional view of a variable load brake apparatus embodying my invention; and Fig. 2 a view of the mechanism by which the variable load brake apparatus is adjusted according to the load on the car.

The construction shown in the drawing is in general, quite similar to that of my pending application hereinbefore referred to and comprises a casing 1 having a vertically disposed piston cylinder 2 containing a piston 3 having a piston stem 4 which slides in a bore 5 of reduced diameter. In the bore 5 is disposed a dash pot piston 6 and interposed between said piston and the end of the stem 4 is a coil spring 41.

A lever 7 is connected to piston stem 4 through a link 8 and a lever 9 is pivotally connected to the free end of lever 7 by means of a pin 10. The opposite end of lever 9 is secured to a rotatable pin 11 and an arm 12 is also secured to said pin. The arm 12 is connected to a rod 13 which in turn is pivotally connected to a rocker arm 14 carried by the car body. A member 15 carried by the car truck is positioned to be engaged by the free end of the rocker arm 15.

A lever 16, fulcrumed on a fixed pin 17 is connected at one end to a link 18 carrying a roller 19 at its free end and the opposite end of the lever 16 is connected through a link 20 to the piston 6. An arm 21 is carried by the lever 16 and is provided at its free end with a toothed segment 22.

Fulcrumed on a pin 23 is a rocker arm having a pawl arm 24 provided with teeth adapted to engage the teeth of the segment 22 and having an arm 25 which is connected to the stem 26 of a piston 27, contained in piston chamber 28. Lever 7 is also connected to lever 16 by a link 63.

Vertically disposed in the casing 1 are

flexible diaphragms 30 and 31, the diaphragm 30 being engaged on one side by a follower plate 32 having a stem 33 which engages a fulcrum plate 34, and the diaphragm 31 being engaged on one side by a follower plate 35 having a stem 36 also engaging the fulcrum plate 34. The fulcrum plate 34 is pivotally supported by a link 37 which is pivotally mounted on the pin 23 and roller 19 is interposed between the face 38 of the plate 34 and a face 39 of a member 40 carried by the casing 1.

The stem of a valve 42 engages the side of diaphragm 31 opposite the follower 35, said valve being subject to the pressure of a spring 43 tending to seat the valve.

A relay valve portion 44 is provided having a piston chamber 45 containing a piston 46 and a valve chamber 47 containing a slide valve 48 adapted to be operated by said piston through a stem 49. A small piston 50 is provided on stem 49 intermediate the piston 46 and the valve 48 and a guide piston 51 is carried by said stem at its outer end. A valve 52 is positioned to be operated by the inward movement of the stem 49 and controls the supply of fluid under pressure from valve chamber 53 to a pipe 54 which leads to the brake cylinder (not shown).

The fulcrum plate 34 is provided with an arm or lug 55 and carried by said arm is an adjustable screw 78 for operating the stem of a pilot release valve 56 for controlling the venting of fluid under pressure from piston chamber 45 through passage 57 to an atmospheric exhaust port 58.

The piston chamber 2 is connected through passage 59 with a pipe 60 which is connected to the car door opening pipe, said pipe being supplied with fluid under pressure in order to open the car doors.

When the car is brought to a stop, fluid under pressure is supplied to pipe 60 to effect the opening of the car doors and is thus supplied to passage 59. The spring 61 acting on piston 27 is of such resistance, as compared with spring 41 acting on piston 3, that fluid under pressure will be effective to move piston 3 before piston 27 is moved. When piston 3 is moved outwardly, since the lever 16 is locked against movement by the engagement of pawl arm 24 with the toothed segment 22 of arm 21, the pin 62 which connects link 63 with said lever acts

as a fulcrum, and the movement of lever 7 about said fulcrum causes a movement of rod 13 to the left, through the movement of the arms 9 and 12.

The rocker arm 14 is thus actuated to cause the free end to engage the member 15.

After the above movement of parts, the piston 27 is shifted outwardly, so that the pawl arm 24 is actuated to disengage the teeth of the pawl from the teeth of the toothed segment 22.

The rod 13 is now free to move according to the load on the car. If the load is increased, the car body will move toward the car truck and thus cause the member 15 to rock the rocker arm 14 and effect a corresponding movement of the rod 13 toward the right.

Piston 3 holds the adjacent end of the lever 7 against vertical movement and the lever 16 being fulcrumed on the pin 17, the movement of the rod 13 toward the right causes a counter-clock-wise movement of arm 9 and the lever 7. The link 63 is thus moved downwardly and causes a counter-clock-wise movement of lever 16 about its fulcrum pin 17, so that the link 18 is pulled downwardly, causing a downward movement of the fulcrum roller 19. Thus the position of the roller 19 is determined according to the load on the car. If the load is decreased, the parts will move in the reverse direction, as will be evident, and the roller 19 will be caused to move upwardly.

When the car is to be started, the car doors are closed and fluid under pressure is vented from pipe 60 and passage 59. Since the spring 61 exerts a greater pressure than spring 41, the release of fluid under pressure from passage 59 first permits the piston 27 to be shifted by spring 61, so that the pawl arm 24 is operated to cause the pawl teeth to engage the teeth of the segment 22. The arm 21 is thus locked against movement while the car is running.

Piston 3 then returns to its normal position, causing the rod 13 to be pulled toward the right, so that the free end of the rocker arm 14 is moved out of engagement with the member 15, thus preventing movement of the parts by the relative movement of the car body with respect to the truck, so long as the car is running.

The piston 6 being connected to lever 16 assumes a position in the bore 5, corresponding with the position of the roller 19.

When the brakes are applied in making a car stop, the triple or other brake controlling valve device is operated to supply fluid under pressure to a volume reservoir or dummy brake cylinder 64, which is connected through pipe 65 and passage 66 with one side of the diaphragm 30. The diaphragm 30 is then moved outwardly, causing the stem 33 to move the plate 34 with

the roller 19 acting as a fulcrum. The stem 36 is thereupon moved toward the left, so as to open the valve 42.

Valve chamber 67 is connected through passage 68 and pipe 69 to a source of fluid under pressure, such as the main reservoir, so that when valve 42 is opened, fluid under pressure is supplied to passage 57, leading to piston chamber 45. Piston 46 is then shifted toward the right, so that slide valve 48 is first operated to close the exhaust ports 70 and then the piston stem 49 engages the stem of valve 52. The valve 52 is then unseated and fluid under pressure is supplied from chamber 53, which is connected to the main reservoir passage 68, to passage 71, which leads to the brake cylinder pipe 54.

When the pressure acting on diaphragm 31 has been increased by flow past the valve 42 to a degree such as to slightly exceed the pressure acting on diaphragm 30, and taking into account the position of the fulcrum roller 19, the diaphragm 31 will move so as to permit the valve 42 to close. Fluid is thus supplied to piston chamber 45 and is bottled up by the closing of valve 42, at a pressure corresponding with the load on the car.

Fluid supplied to the brake cylinder is also supplied through passage 72 and a restricted port 73 to the chamber between the pistons 46 and 50, and when the pressure in said chamber has been increased to a degree corresponding with the pressure in piston chamber 45, the piston 46 is moved so as to permit the valve 52 to close. The pressure of fluid supplied to the brake cylinder is thus proportional to the pressure of fluid in piston chamber 45 and consequently to the load on the car.

The pressure in the brake cylinder may be graduated on, by increasing the pressure of fluid in the dummy brake cylinder 64, through the operation of the usual brake controlling valve device.

In releasing the brakes, if the fluid under pressure in the dummy brake cylinder 64 is exhausted by operation of the brake controlling valve device, the pressure on diaphragm 30 is reduced, so that the fluid pressure acting on diaphragm 31 acts on the plate 34 so as to rock same in a direction to open the release pilot valve 56. The opening of pilot valve 56 causes fluid under pressure to be vented from piston chamber 45, permitting the brake cylinder pressure acting on the opposite side of the piston to shift said piston to its release position, in which the exhaust ports 70 are open to valve chamber 47, thus permitting fluid under pressure to be exhausted from the brake cylinder.

The brakes may be wholly released, if the fluid under pressure in the dummy brake cylinder 64 is wholly exhausted by operation of the brake controlling valve device. If,

however, the fluid in the dummy brake cylinder is partially released in order to effect a graduated release of the brakes, then the release valve 56 will only be held open until the pressure in piston chamber 45 and on the diaphragm 31 has been reduced to a degree corresponding with the degree to which the pressure acting on the diaphragm 30 has been reduced. As soon as the release pilot valve 56 closes, further reduction in pressure in the brake cylinder permits the higher pressure in piston chamber 45 to shift piston 46 so as to operate the slide valve 48 and close the exhaust ports 70.

15 It will thus be seen that the pressure in the brake cylinder will be graduated off in proportion to the load on the car and corresponding with the graduations in pressure in the dummy brake cylinder 64.

20 When the parts are in an adjusted position, with the pawl arm 24 in locking position, the piston 6 is in some position in bore 5, dependent upon the previous adjustment of the parts according to the load on the car. 25 If, for any reason, the piston 27 should move before the piston 3, then the release of the pawl 24 permits the spring 41 to throw the piston 6 downwardly and with considerable force against the cylinder head 75. In order to prevent such sudden movement of the piston 6, said piston is provided with a piston ring 76 and through the piston a restricted port 77 is provided. By this arrangement, the piston 6 moves gradually, according to the rate fluid can escape through the port 77 and thus the piston is prevented from striking a sharp blow on the cylinder head.

30 Having now described my invention, what I claim as new and desire to secure by Letters Patent, is:—

40 1. In a variable load brake, the combination with a brake cylinder, of a valve device for controlling the release of fluid from the brake cylinder, a valve for controlling said valve device, and mechanism adjusted according to the load on the car for operating said valve.

45 2. In a variable load brake, the combination with a brake cylinder, of a valve device for controlling the admission and release of fluid under pressure to and from the brake cylinder, valve means for controlling the operation of said valve device, and mechanism adjusted according to the load on the car for operating said valve means.

50 3. In a variable load brake, the combination with a brake cylinder, of a valve device operated by variations in fluid under pressure for controlling the admission and release of fluid under pressure to and from said brake cylinder, a valve for supplying fluid under pressure to said valve device, a valve for venting fluid under pressure from

said valve device, and means adjusted according to the load on the car for operating 65 said valves.

4. In a variable load brake, the combination with a brake cylinder, of a valve device subject to the opposing pressures of the brake cylinder and a chamber for controlling 70 the admission and release of fluid under pressure to and from said brake cylinder, valve means for controlling the pressure of fluid in said chamber, and means adjusted according to the load on the car for operating said 75 valve means.

5. In a variable load brake, the combination with a brake cylinder, of a valve device subject to the opposing pressures of the brake cylinder and a chamber for controlling 80 the pressure in the brake cylinder, a fulcrumed member, a flexible diaphragm operated by variations in fluid under pressure for operating said member, a valve operated by said member for varying the pressure of fluid in said chamber, and means operated according to the load on the car for adjusting 85 the fulcrum of said member.

6. In a variable load brake, the combination with a brake cylinder, of a valve device subject to the opposing pressures of the brake cylinder and a chamber for controlling 90 the pressure in the brake cylinder, a fulcrumed member, a flexible diaphragm operated by variations in fluid under pressure 95 for operating said member, a valve operated by said member for varying the pressure of fluid in said chamber, a flexible diaphragm subject to the pressure of fluid in said chamber for also controlling the operation of said 100 valve, and means operated according to the load on the car for adjusting the fulcrum of said member.

7. In a variable load brake, the combination with a brake cylinder, of a valve device 105 for controlling the release of fluid from the brake cylinder, a valve for operating said valve device, a fulcrumed member for operating said valve, and means operated according to the load on the car for adjusting the 110 fulcrum of said member.

8. In a variable load brake, the combination with a brake cylinder, of a valve device 115 subject to the opposing pressures of the brake cylinder and a chamber and operated by venting fluid from said chamber for releasing fluid from the brake cylinder, a valve for venting fluid from said chamber, a fulcrumed member for operating said valve, and means operated according to the load on 120 the car for adjusting the fulcrum of said member.

In testimony whereof I have hereunto set my hand.

THOMAS H. THOMAS.
